CLAIM

We claim the ornamental design for a cover panel for window air conditioner, as shown and described.

DESCRIPTION

FIG. 1 is a front perspective view of a cover panel for window air conditioner showing our new design;

FIG. 2 is a rear perspective view thereof;

FIG. 3 is a front elevation view thereof;

FIG. 4 is a rear elevation view thereof;

FIG. 5 is a left-side elevation view thereof, a right-side elevation view being a mirror image thereof;

FIG. 6 is a top plan view thereof;

FIG. 7 is a bottom plan view thereof;

FIG. 8 is an enlarged view of portion 8 in FIG. 2;

FIG. 9 is another enlarged view of portion 8, showing the cover panel for window air conditioner in an alternate configuration; and,

FIG. 10 is a front perspective view of the cover panel for window air conditioner, shown in an environment of use. The evenly-spaced broken lines in FIGS. 1-9 depict portions of the cover panel for window air conditioner that form no part of the claimed design. The dot-dot-dash broken lines shown in FIGS. 2 and 8 indicate the enlargement area that form no part of the claimed design. The dot-dash broken lines shown in FIG. 9 indicate the enlargement area that form no part of the claimed design. The evenly-spaced broken lines and the dot-dot-dash broken lines in FIG. 10 respectively illustrate an environmental structure and a boundary of a view with environment that form no part of the claimed design.
